A. McGINNIS

GAME DEVICE

Filed July 15, 1921

FIG. 1.

FIG. 2.

Inventor

Arthur McGinnis

By his Attorneys

Edgar Gatehouse

UNITED STATES PATENT OFFICE.

ARTHUR McGINNIS, OF NEW YORK, N. Y.

GAME DEVICE.

Application filed July 15, 1921. Serial No. 485,002.

To all whom it may concern:

Be it known that I, ARTHUR McGINNIS, a citizen of the United States, and residing at New York, in the county of New York and State of New York, have invented certain new and useful Improvements in Game Devices, of which the following is a specification, such as will enable those skilled in the art to which it appertains to make and use the same.

This invention relates to game devices, and the object thereof is to provide an improved device of this class which is simple in construction, inexpensive and designed to amuse both old and young.

The invention is fully disclosed in the following specification, of which the accompanying drawing forms a part, in which the separate parts of my improvement are designated by suitable reference characters in each of the views, and in which:—

Fig. 1 is a side view of a device of the class specified involving my invention; and Fig. 2 a plan view thereof.

The general structure of my improved game device is similar to that of an ordinary top as shown at a , and said device comprises an oblong body portion a^2 , the bottom of which is tapered or rounded to form a spinning point a^3 and the rim of the top portion is rounded or beveled as shown at a^4 , and said top portion is provided with a central projecting pin a^5 whereby the top may be spun in the usual manner.

The oblong body portion a^2 is provided with a plurality of longitudinal faces a^6 , said faces, in the form of construction shown, being eight in number, and placed on these faces, in the construction shown, are the names of eight of the cards of an ordinary deck of playing cards, the cards selected, in this case, being ace, king, queen, jack, ten, nine, eight and seven.

In playing the game a score card is provided in the usual manner, said card being provided with a column for each player, and said card is also preferably provided with the names of the different cards employed and adjacent to which are placed numerals representing the value given to said cards in the playing of the game.

In playing the game, supposing that seven are engaged, any player may first spin the top and if in spinning the top the word "Ace" comes up as shown in Fig. 1 of the drawing, the player counts in his column on the score card the numerical value of the word "Ace," and this continues successively among the players until all have spun the top once, and a player who gets the highest number wins the game. A game may consist, however, of a number of rounds of spinning the top in which each player engages, and if said number of rounds are fixed as five, the spinning of the top is continued until each player has spun the top five times, and each spinning of the top by any player is counted on the score card in the manner above described, and at the end of the five rounds of spinning the top, the score card is footed up and the party making the highest number of points wins the game.

It will be understood that my invention is not limited to any particular eight cards in a pack of cards nor to any particular value given to said card in counting the game, nor to any particular method of playing said game, and changes in and modifications of the construction or arrangement of parts herein shown and described and in the method of playing the game, as herein set out, may be made, within the scope of the appended claims, without departing from the spirit of my invention, or sacrificing its advantages.

Having fully described my invention, what I claim as new and desire to secure by Letters Patent, is:—

1. A game device comprising a top, the body portion of which is octagon in form or provided with eight longitudinal faces on which are placed characters designating ace, king, queen, jack, ten, nine, eight and seven of a deck of cards, and the lower end portion of the top being substantially hemispherical in form.

2. A game device comprising a top, the body portion of which is octagon in form or provided with eight longitudinal faces on which are placed characters designating ace, king, queen, jack, ten, nine, eight and seven

of a deck of cards, the lower end portion of the top being substantially hemispherical in form, and the upper end portion of the top being provided with a reduced handle portion, by means of which the device may be spun.

In testimony that I claim the foregoing

as my invention I have signed my name in presence of the subscribing witnesses this 14th day of July, 1921.

ARTHUR McGINNIS.
